CHAIMSONOVITZ PROSPER ELIESON, OF LONDON, ENGLAND, ASSIGNOR OF TWO-THIRDS
TO J. AND A. CARTER, OF LONDON, ENGLAND.

ELECTRICALLY-PROPELLED INVALID-CHAIR.

1,189,195.

Specification of Letters Patent. Patented June 27, 1916.

Application filed May 22, 1916. Serial No. 99,206.

To all whom it may concern:

Be it known that I, CHAIMSONOVITZ PROSPER ELIESON, a subject of the King of Great Britain, residing at London, England, have 5 invented certain new and useful Improvements in Electrically-Propelled Invalid-Chairs, of which the following is a specification.

This invention relates to improvements in 10 electrically propelled invalid chairs or like light vehicles, and has particular reference to the means for supporting the electric motor and for transmitting the power from the motor to the front wheel axle so as to 15 insure an efficient drive while permitting of oscillatory movement of the front axle for steering purposes.

The invention and the details thereof will 20 be more clearly understood from the following description of one convenient form employing two front steering and driving wheels.

In the drawings:—Figure 1 is a side elevation of an invalid chair with the motor attached. Fig. 1^a is a plan of a steering bracket. Fig. 2 is a plan of part of the frame of the chair, part of the motor support, and means for fixing the motor support to the frame of the chair. Fig. 3 is an elevation corresponding therewith. Fig. 4 is a 25 sectional elevation of the motor, its support, the front wheel axle casing and steering tube, the section being taken on the irregular line IV.—IV. Fig. 1, parts of the motor support being broken away. Fig. 4^a is a plan of a detail. Fig. 5 is a transverse section through the front axle and worm gear casting showing the worm and worm gear.

The bath or invalid chair is of ordinary 40 construction. Beneath the seat and in front of the rear axle there is provided a box *a* in which the accumulators are placed. The current supply is led from the accumulators to a switch *b* and thence by a conduit *c* to the 45 motor in the casing *d*. As these details may be of any ordinary construction well known in the art and do not form parts of the present invention no further description need be given. The motor casing *d* is suitably 50 ventilated and the motor *M* is supported by and fixed to a support *e* which has arms *f* by which it is fixed to the frame *g* of the chair, the arms *f* having clamping

plates *h* which rest on lugs *g'* and are pulled onto the frame *g* by bolts *g*². A bolt *h'* 55 passes through an extension *h*² on the support *e*, and through the frame *g*, while a yoke *i* is secured by a bolt *h*³ to the upper part of the motor support *e*. The motor support *e* is thus rigidly fixed to the frame 60 of the chair at four points *h*, *h*, *h'*, *h*³. The flange *j* on the motor support *e* has passing through it the bolts *k* which secure the motor to the support. It will be seen that the motor is supported with its axis of rotation 65 substantially vertical.

The weight of the front part of the chair is transmitted through the frame *g*, arms *f*, to a ball thrust bearing *m* located to act between the motor support *e* and a rotatable 70 steering tube *n* (see Fig. 4). The ball thrust bearing *m* is arranged in a recess in the support *e* and an outer tube *o* on the tube *n* acts as a support thereto. The outer tube *o* is suitably fixed to the inner tube *n* as by a 75 screw *o'* and also forms a distance piece between the thrust bearing *m* and the casing *p* for the front wheel axle. A bracket *q* clamped to the outer tube *o* carries the steering rod *r*. The bracket is split as shown in 80 Fig. 1^a and has a clamping bolt *q'*.

The casing *p* is made in two parts which join in a vertical plane and are screwed together by screws *w'*, Fig. 1, the holes *w*² for which are shown in Fig. 5 where one half of 85 the casing is removed. The casing *p* contains the front wheel axle *s*^a, the worm wheel *w* and the worm shaft *s*. The worm shaft is mounted in suitable ball bearings *t* and ball thrust bearings *20*, *20*, are provided. 90 The steering tube *o* is slotted at *v* to allow the worm wheel *w* to pass.

Between the motor shaft *x* and the worm shaft *s* there is an intermediate driving shaft *6* which provides a flexible transmission between these two parts so that they may run freely in spite of any lack of accuracy in alinement or of vibration. A convenient and simple form for this flexible drive is shown and consists of sockets *y* and 100 *z* on the motor shaft *x* and the worm shaft *s* respectively. These sockets have side slots. On the extremities of the intermediate length *6* there are provided ball ends *7* carrying side projections or feathers *8* which 105 work in the slots in the sockets.

The lower part of the worm wheel casing *p'* forms an oil bath which effectively lubricates the driving parts. The worm wheel *w* is mounted loosely on the front wheel axle *8^a* and is held against axial movement in both directions by a collar 9 and a split collar 10. The split collar 10 has a flange 20 which engages in an external groove 21 in the hub of the worm wheel *w* and the halves 10 are held in place by screws 11, which also secure the collar 9 to the axle *8^a*. On the opposite side to the collars 9 and 10 the hub of the worm wheel *w* is provided with clutch teeth 12 with which there engage corresponding teeth on a sliding clutch 13 keyed by a feather 23 to the axle *8^a*. A sliding finger grip 14 incloses a plunger 24 which is connected by a rod 25 to a loose ring 26 which is mounted on the clutch 13. By raising the finger grip 14 against a spring 15 the neck 27 of the grip is pulled out of a hole 28 in the casing *p*. The clutch 13 can then be moved into engagement with the teeth 12. In this position the grip is released and the spring 15 returns the neck into a second hole 29 in the casing. The two holes 28 and 29 interpenetrate with each other.

The front wheels 17 are fixed to the axle *8^a* and ball bearings 16 are provided to insure easy running.

It will be seen that the whole of the motor and motor support, together with the steering tube and front axle may be detached from or attached to the frame of the chair. It may thus be made and sold as a separate unit if desired.

I claim:—

1. For use on an invalid chair or like light vehicle, a motor support comprising a vertical tubular member having at its upper end a motor housing and adapted to be fixed to the frame of the chair, an electric motor secured in the motor housing, a front wheel axle below and spaced from the motor housing, gearing for driving said axle, a casing for said axle and said gearing, said casing having a vertical tubular extension, means for rotatably mounting the tubular extension in the lower end of the tubular member of the motor support, and driving means including a flexible shaft between the motor and said gearing.

2. For use on an invalid chair or like light vehicle, a motor support comprising a vertical tubular member having at its upper end a motor housing and adapted to be fixed to the frame of the chair, an electric motor secured in the motor housing, a front wheel axle below and spaced from the motor housing, gearing for driving said axle, a casing for said gearing and axle, said casing having a steering tube, means for rotatably mounting the steering tube in the lower end of the vertical tubular member of

the motor support, a tube fastened on the inside of the steering tube and extending through the tubular member of the motor support, driving means including a flexible shaft between said motor and said gearing, and means for rotating said steering tube for steering purposes.

3. For use on an invalid chair or like light vehicle, a motor support adapted to be fixed to the frame of the chair, an electric motor on said support, a front wheel axle, a worm wheel on said axle, means for securing said worm wheel to said axle, a worm shaft meshing with said worm wheel, a casing for said axle, worm shaft and worm wheel, a steering tube connected to said casing and pivotally mounted in said motor support, a driving shaft connecting said motor and said worm shaft, and means for moving said steering tube relatively to said motor support for steering purposes, substantially as hereinbefore set forth.

4. For use on an invalid chair or like light vehicle, a motor support adapted to be fixed to the frame of the chair, an electric motor on said support, a front wheel axle, a worm wheel freely mounted on said axle, a clutch for detachably securing said worm wheel to said axle, a worm shaft meshing with said worm wheel, a casing for said axle, worm shaft and worm wheel, a steering tube connected to said casing and pivotally mounted in said motor support, a driving shaft connecting said motor and said worm shaft, and means for moving said steering tube relatively to said motor support for steering purposes, substantially as hereinbefore set forth.

5. For use on an invalid chair or like light vehicle, a motor support adapted to be fixed to the frame of the chair, an electric motor on said support, a front wheel axle, a worm wheel on said axle, a worm shaft meshing with said worm wheel, a casing containing said axle, worm wheel and worm shaft, said casing having ball bearings for said axle and said worm shaft, a steering tube fixed to said casing and pivotally mounted in said motor support, a ball thrust bearing carried by said steering tube and supporting said motor support, a flexible driving connection between the aforesaid electric motor and said worm shaft, and means for rotating said steering tube for steering purposes, substantially as hereinbefore set forth.

6. For use on an invalid chair or like light vehicle, a motor support having lateral arms, clamps at the ends of the lateral arms for clamping said support to the frame of the chair, said support having a vertical tubular member and a motor housing at the upper end thereof, an electric motor supported in the housing, a gear casing, an axle and gearing in said casing, two front wheels on said axle, means for rotatably mounting said

gear casing to the lower end of the tubular member on the motor support, driving means including a flexible shaft between the electric motor and said gearing, and means for moving said gear casing relatively to the motor support for steering purposes.

5 In testimony whereof I have signed my

name to this specification in the presence of two subscribing witnesses.
